UNITED STATES PATENT OFFICE.

FREDERICK W. VINTON, OF WEEHAWKEN, NEW JERSEY.

LANTERN.

No. 866,242.

Specification of Letters Patent.

Patented Sept. 17, 1907.

Application filed October 20, 1906. Serial No. 339,792.

To all whom it may concern:

Be it known that I, FREDERICK W. VINTON, a citizen of the United States, residing at Weehawken, in the county of Hudson and State of New Jersey, have invented certain new and useful Improvements in Lanterns, of which the following is a specification, reference being had thereto to the accompanying drawings, which form a part thereof.

My invention relates to lanterns and more particularly to a class of signal lanterns.

The main object of the invention is to provide a lantern wherein the light may be made to show either white or another color, as red or green, in order to combine in a single lantern both a safety and a danger or caution signal, and to permit a single lantern to be used for general purposes and also for signaling.

A further object is to provide a lantern of this type wherein the change from safety to danger or caution, or vice versa, may be made instantly.

20 A still further object is to provide a lantern of this type wherein the light will show the same color throughout, and the globe will be so positioned that only one color can show at a time.

25 A still further object is to provide a lantern of this type employing a permanent white globe and an auxiliary colored globe wherein the colored globe will be held in a manner to permit its being readily brought into its operative position and to prevent such looseness thereof under any circumstances, as would make it liable to breakage thus destroying the utility of the lantern as a danger or caution signal.

30 A still further object is to provide a lantern of this type wherein the colored globe when raised will be held in this position in a manner to prevent its displacement through jars or vibrations.

35 A still further object is to provide an attachment applicable to the type of signal lanterns now commonly used.

40 A still further object is to provide a lantern of this type wherein the parts may be readily cleaned, and the tank refilled.

45 A still further object is to provide a globe support for the white globe which will leave a clear field within it for the auxiliary or color globe. And a still further object is to provide a lantern which will embody there-in a main colorless globe and an auxiliary colored globe, the construction and arrangement of which will be simple and which will be inexpensive to produce.

The invention consists primarily in the combination 50 in a signal lantern of a base, means supported thereby producing a light, a substantially colorless globe surrounding said means, a support therefor carried by said base, an auxiliary colored globe and means whereby said auxiliary globe may be moved to cause it to be hid-

den or to surround said light producing means whereby 55 said lantern may be made to show substantially white or a color; and in such other novel features of construction and combination of parts as are hereinafter set forth and described and more particularly pointed out in the claims hereto appended.

60 Referring to the drawings: Figure 1 is a perspective view of a lantern embodying my invention; Fig. 2 is a sectional elevation thereof; Fig. 3 is a perspective view of the auxiliary globe; Fig. 4 is a plan view of the top plate for the white globe, and Fig. 5 is a perspective view of the auxiliary globe support.

Like letters refer to like parts throughout the several views.

In the embodiment of my invention shown in the drawings, I have illustrated the application of the invention to a type of lantern now in general use as a signal lantern, and will describe it with relation more particularly thereto. In said drawings, I have shown a base composed of a lower detachable section *a* which has an oil tank *b* secured thereto, and an upper section 75 *c*, the said sections being secured together temporarily in the usual and well known manner. The section *c* carries the guard frame composed of a plurality of suitably shaped vertical guard wires *d* and horizontal wires *d'*, the top hood *e* being supported by said frame in the usual manner. The top of the section *c* is provided with a flanged seat *e'* for the permanent globe *f*, the dome *e''* of the top hood having mounted therein a plate *g* adapted to bear upon the top of the globe *f* and hold it upon its seat *e'*. Said plate *g* is movable and is subjected to a constant downward pressure from a coiled spring *g'* bearing upon the top of said dome *e''* and adjacent to the edge of said plate. To provide the proper draft for the burner *b'* carried by the tank *b* the plate *g* is pierced adjacent to the edge thereof, allowing sufficient surface to engage the globe, and the segments so formed are turned upwards in the usual manner.

The hand bail *h* is attached to the lantern in the usual manner.

Between the sections *a*—*c* and the oil tank *b* a well 95 is formed, thus providing a clear space entirely surrounding the tank and its appurtenances. In the ordinary lantern, this well is found, but if a special type of lantern is made such should be provided preferably, such being the most convenient place for hiding or obscuring the colored auxiliary globe. Seated in the said well with its top frame normally below the level of the burner *b'* is a movable frame composed of a spring wire bottom frame *i*, a wire head *j* and a plurality of outwardly bowed connecting wires *k* also of 100 spring wire. The wires *k* are so bowed as to frictionally engage the inner side of the base, the spring inherent thereto being such as to hold the frame in po

sition when lowered and to sustain the weight thereof and of the contained colored globe *m* when raised.

The bottom frame *i* is preferably made of a continuous strand of spring wire formed into a loop having 5 one end free and the other end projected radially of the loop to form an extension *i'* to a point without the section *a* and upwardly to form a handle *i''* by means of which the entire frame may be raised and lowered. The handle *i''* is turned outwardly and is adapted to 10 extend over and engage one of the lower guard wires *d'* when lowered. A notch or recess *i''* is formed in said handle at a point thereof which when raised will engage one of the upper guard wires *d'*, the spring in said handle holding it in such engagement and aiding in 15 sustaining the weight of the frame and the contained globe *m*.

The lower edge of the globe *m* is preferably recessed at *m'* to provide a seat whereby the weight of the globe will come upon the bottom frame *i*.

20 1 I preferably cut registering slots in the sections *a* to form a way for the extension *i'* and provide said sections with housings *n* *n'* inclosing said handle.

The operation of the lantern is substantially as follows: Normally the parts will be in the position shown 25 in Fig. 1 and in the full lines Fig. 2, the frame from the burner *b'* showing white through the globe *f*. When in this position, the lamp may be used by conductors, brakemen, trainmen, and signal men in giving starting, backing and safety signals, and in all the ordinary uses to which the white lanterns are now put. The lantern being in such use is always carried with the user, and being swung about more or less violently, the globe *m* being entirely surrounded by metal, would be liable to breakage, were it not that the springs *k* 30 bear upon the outer walls of the well within which the globe rests and absorb all shocks and jars. The globe *m* being below the level of the flame from the burner *b'*, and being held firmly in this position, there is no danger of an accidental change from white to red or 40 green through a shifting of the auxiliary globe, while giving signals, nor of the light showing through any part of said globe. In fact the auxiliary globe under normal conditions, is completely hidden, and the lantern to all intents and purposes is only an ordinary 45 white lantern. If however, it is desired to give a caution or danger signal, it is merely necessary for the holder of the lantern to grasp the handle *i''* with the free hand and draw the frame carrying the globe *m* upwards, thus causing it to instantly entirely surround 50 the burner, and cause the lantern to show green or red according to the color of the auxiliary globe. As the frame rises, the arms *k* steady the globe and when it reaches the limit of its upward movement, the bow of said arms offers sufficient resistance against the inner edge of the seat *c'* to sustain the weight of the frame and globe. The notch *i''* will, however, simultaneously engage one of the upper guards *d'* and aid in sustaining this weight as well as in preventing a slight pressure on the handle *i''* lowering the frame. 60 When so raised, the said bows *k* and handle *i''* will both prevent looseness of the globe *m* and any accidental change of the signal. The loose spring pressed cap *g* serves merely to compensate for the irregularities in the heights of globes, *f*, and to allow for the expansion 65 and contraction thereof. If it is desired to place or

remove the auxiliary globe *m* in or from its frame, it is merely necessary to draw out the free end of the bottom frame *i* and insert or withdraw the globe through the enlarged loop thus provided. When inserted, the said bottom frame *i* will at once spring to 70 place when released, about the recessed bottom of said globe.

It will be observed that with the herein described type of lantern, a single lantern may be used for practically all signals, and that inasmuch as in the railway 75 service, the conductors, trainmen, brakemen or signalmen, always carry the white lantern with them, in case of emergency, this lantern may be instantly caused to show red, thus avoiding the necessity for procuring the red lantern which ordinarily is kept at 80 a point which is concealed from the engineer.

In addition to the economy of a single set of lanterns instead of a double set throughout, it will be observed that the use of the auxiliary globe will serve to avoid 85 a loss of time or confusion of signals, in case of emergencies.

It is not my intention to limit the invention to the precise details of construction shown in the drawings, such being merely the adaptation of the invention to one well known type of lantern. The invention is 90 capable of such variations as may be necessary to adapt it to different styles of lanterns. While I have shown and described an ordinary oil burner as the source of light, it is apparent that such is not material to the invention except broadly, any source of light being 95 all that is required.

Having described the invention, what I claim as new and desire to have protected by Letters Patent is:

1. A lantern comprising a base having a well therein, means supported thereby producing a light, a substantially colorless globe surrounding said means and above said well, a support therefor carried by said base, an auxiliary colored globe, a reciprocating frame comprising a bottom frame adapted to support said auxiliary globe and spring arms carried by and movable with said bottom frame adapted to inclose said auxiliary globe and to engage the wall of said well, and means exposed exteriorly of said base whereby said frame may be moved to cause said auxiliary globe to be hidden in said well or to surround said light producing means whereby said lantern may be made to show substantially white or a color. 100

2. A lantern comprising a base having a well therein, means supported thereby producing a light, a substantially colorless globe surrounding said means and above said well, a support therefor carried by said base, an auxiliary colored globe, a reciprocating frame comprising a bottom frame, a top frame and outwardly bowed spring arms connecting said top and said bottom frame adapted to engage the wall of said well, and means exposed exteriorly of said base whereby said frame may be moved to cause said auxiliary globe to be hidden in said well or to surround said light producing means whereby said lantern may be made to show substantially white or a color. 105

3. A lantern comprising a base having a well therein, means supported thereby producing a light, a top and vertical and horizontal guards connecting said base and said hood, a substantially colorless globe within said guards surrounding said means and above said well, a support therefor carried by said base, an auxiliary colored globe, a reciprocating frame comprising a bottom frame, a top frame and outwardly bowed spring arms connecting said top and said bottom frame adapted to engage the wall of said well, and a handle attached to said frame extending upwardly exteriorly of said base adapted to engage said horizontal guards to aid in sustaining the weight of said frame and said auxiliary globe whereby said frame may be moved to cause said auxiliary globe to be hidden in said 110 115 125 130 135

well or to surround said light producing means whereby said lantern may be made to show substantially white or a color.

4. A lantern comprising a base having a well therein, a flange seat above said well, means supported by said base producing a light, a hood, vertical and horizontal guards connecting said base and said hood, a substantially colorless globe on said seat within said guards surrounding said means, an auxiliary color globe, a reciprocating frame comprising a bottom frame, a top frame and outwardly bowed spring arms connecting said top and said bottom frame adapted to engage the wall of said well, and a handle attached to said frame extending upwardly exteriorly of said base adapted to engage said horizontal guards to aid in sustaining the weight of said frame and said auxiliary globe whereby said frame may be moved to cause said auxiliary globe to be hidden in said well or to surround said light producing means whereby said lantern may be made to show substantially white or a color.
5. A lantern comprising a base having a well therein, a flange seat above said well, means supported by said base producing a light, a hood, vertical and horizontal guards connecting said base and said hood, a substantially colorless globe on said seat within said guards surrounding said means, an auxiliary colored globe, a reciprocating frame comprising a spring metal bottom frame forming a loop open at one point, a top frame and outwardly bowed spring arms connecting said top and said bottom frame adapted to engage the wall of said well, and a handle attached to said frame extending upwardly exteriorly of said base adapted to engage said horizontal guards to aid in sustaining the weight of said frame and said auxiliary globe whereby said frame may be moved to cause said auxiliary globe to be hidden in said well or to surround said light producing means whereby said lantern may be made to show substantially white or a color.
6. A lantern comprising a base formed of two interlocking sections, a receptacle carried by one of said sections and spaced within same whereby a well is formed between said receptacle and said base, a flanged seat carried by the other section above said well so formed, a hood, vertical and horizontal guards connecting said base and said hood, means carried by said receptacle producing light, a substantially colorless globe on said seat within said guards surrounding said means, an auxiliary colored globe, a reciprocating frame comprising a spring metal bottom frame forming a loop open at one point, a top frame and outwardly bowed spring arms connecting said top and said bottom frame adapted to engage the wall of said well, and a handle attached to said frame extending upwardly exteriorly of said base adapted to engage said horizontal guards to aid in sustaining the weight of said frame and said auxiliary globe whereby said frame may be moved to cause said auxiliary globe to be hidden in said well or to surround said light producing means whereby said lantern may be made to show substantially white or a color.
7. A lantern comprising a base having a well therein, a flange seat above said well, means supported by said base producing a light, a hood, vertical and horizontal guards connecting said base and said hood, a substantially colorless globe on said seat within said guards surrounding said means, an auxiliary colored globe, a reciprocating frame comprising a spring metal bottom frame forming a loop open at one point, a top frame and outwardly bowed spring arms connecting said top and said bottom frame adapted to engage the wall of said well, and a handle attached to said frame extending upwardly exteriorly of said base adapted to engage said horizontal guards to aid in sustaining the weight of said frame and said auxiliary globe whereby said frame may be moved to cause said auxiliary globe to be hidden in said well or to surround said light producing means whereby said lantern may be made to show substantially white or a color.

In witness whereof, I have hereunto affixed my signature, this 10th day of October, 1906, in the presence of two witnesses.

FREDERICK W. VINTON.
